US0D1046576S

(12) **United States Design Patent** (10) Patent No.: **US D1,046,576 S**
(45) Date of Patent: ** Oct. 15, 2024

(54) **LOG SPLITTER**

(71) Applicant: **INDUSTRIAL SUPPLY (QINGDAO) LTD.**, Qingdao (CN)

(72) Inventors: **Wensheng Xu**, Qingdao (CN); **Jinde Song**, Qingdao (CN)

(73) Assignee: **INDUSTRIAL SUPPLY (QINGDAO) LTD.**, Qingdao (CN)

(**) Term: **15 Years**

(21) Appl. No.: **29/923,350**

(22) Filed: **Dec. 28, 2023**

Related U.S. Application Data

(63) Continuation-in-part of application No. 29/823,429, filed on Jan. 17, 2022, now Pat. No. Des. 1,016,581.
